(57) **CLAIM**

The ornamental design for a vertical stud, as shown and described.

DESCRIPTION

FIG. 1 is a front/right/top perspective view of the first embodiment of the vertical stud showing my new design, shown broken in the center with a double line to indicate that no particular length is claimed.

FIG. 2 is a right side elevation view thereof. The left side is identical to the right side.

FIG. 3 is a front side elevation views thereof. The rear side is identical to the front side.

FIG. 4 is a top view thereof. The bottom view is identical to the top view.

FIG. 5 is a front/right/top perspective view of the second embodiment of the stud showing my new design, shown broken in the center with a double line to indicate that no particular length is claimed.

FIG. 6 is a right side elevation view of the second embodiment.

FIG. 7 is a left side elevation view of the second embodiment.

FIG. 8 is a front view of the second embodiment. The rear side is identical to the front side; and,

FIG. 9 is a top view of the second embodiment. The bottom view is identical to the top view.
